UNITED STATES PATENT OFFICE

156,602

PINCUSHION

Faith E. Callahan, Balboa Island, Calif.

Application April 19, 1948, Serial No. 145,817

Term of patent 7 years

(Cl. D3—19)

To all whom it may concern:

Be it known that I, Faith E. Callahan, citizen of the United States of America, residing in Balboa Island, in Orange County, State of California, have invented a new, original, and ornamental Design for a Pin Cushion, of which the following is a specification, reference being had to the accompanying drawing, forming a part thereof.

Fig. 1 is a front elevational view of a pin cushion, showing my new design;

Fig. 2 is a rear elevational view thereof; and
Fig. 3 is a plan view thereof.

I claim:

The ornamental design for a pin cushion, as shown.

FAITH E. CALLAHAN.
